UNITED STATES PATENT OFFICE.

ANTON PINTER, OF PHILADELPHIA, PENNSYLVANIA.

KNOCKDOWN FOLDABLE BOAT.

1,314,899.

Specification of Letters Patent. Patented Sept. 2, 1919.

Application filed October 3, 1918. Serial No. 256,660.

To all whom it may concern:

Be it known that I, ANTON PINTER, a subject of the ruler of Hungary, residing at Philadelphia, in the county of Philadelphia and State of Pennsylvania, have invented certain new and useful Improvements in Knockdown Foldable Boats, of which the following is a specification.

This invention relates to boats, and pertains especially to a knock down foldable boat of novel and peculiar construction.

The object of the invention is to provide a boat the parts of which are capable of being disassembled for packing and transportation, and adapted to be assembled for use as desired.

A further object of the invention is to provide a folding boat of such novel and peculiar construction and arrangement of parts as to be expeditiously set up for use and knocked down and folded in compact form for packing, carrying or transporting, and to furnish special means and devices for connecting the foldable bottom, sides and rear ends of the boat.

A still further object of the invention is to provide a flexible waterproof cover for foldable sides, bottom and end of the boat, to furnish special means for detachably connecting the cover, and to furnish inflatable side floats attached to the sides of the boat for balancing the boat and affording buoyancy in operating the boat.

In the accompanying drawings forming part of this application:—

Figure 1 is a perspective view of my improved boat with the floats or buoys inflated, and with the cover partly broken away.

Fig. 2 is a sectional elevation without the cover and sides.

Fig. 3 is a similar view with the sides in position.

Fig. 4 is a detail elevation of part of one of the sides of the boat folded.

Fig. 5 is a perspective view of the bottom folded.

Fig. 6 is a perspective view showing frame members folded.

Fig. 7 is a perspective view of the seat.

The same reference characters denote the same parts throughout the several views of the drawings.

In carrying out my invention I employ a set of lazy tongs 1 for the sides, a like set 55 of lazy tongs 2, for the rear end of the boat,

and a foldable bottom composed of a plurality of members 3 laced together lengthwise by a continuous lacing 4, forming hinges 6 between the members 3. The forward member 7 of the bottom has a hole 8 for a stanchion 9, and this member as well as the other members 3 are supported by an angle iron bottom frame comprising a plurality of sections 10. This frame is duplicated in sections 11 which form the upper frames of the boat, and said frames are bolted at the corners 12 to the rear end of the upper and lower frames which comprise sections 13 and 14 respectively. The front end of the upper and lower frames are joined together by the stanchion 9, and the rear end frame holds a post 15 upon which is mounted a handle 16 to which is attached a rudder comprising a plurality of members 17 detachably connected endwise as at 18. Special 75 seats as 21 are provided for the boat.

The cover 19 may be composed of any of the well known waterproof canvases or other materials, and is attached to the side and end frames as at 20, so as to cover the bottom, sides and end of the boat, and is adapted to be removed and folded. The foldable bottom is not attached to its supporting frame but rests loosely thereupon. The bottom, side and end lazy tongs are 85 clamped in open position by the side and end frames and are adapted to be removed therefrom for folding, when the frame is disconnected. The side and end frame members are bolted endwise by means of connecting 90 plates 22, so that said members may be disconnected and nested for packing and transportation. The cover has a pair of inflatable floats or buoys 23.

It will be seen that all parts of the boat 95 are capable of separation or detachment for separate folding and nesting into compact shape for packing and carrying in an ordinary traveling trunk or case, and that said parts may be expeditiously assembled without special tools or implements.

I do not wish to confine my improved boat to any particular size, shape and material, nor to the number of sections or members comprising the various parts, but reserve the right to make such changes and variation in the manufacture and practical application of the invention as may come within the scope of the appended claims.

Having thus described my invention, what 110

I claim as new and desire to secure by Letters Patent, is:

1. In a foldable boat, upper and lower side and end frames comprising angle iron sections detachably connected, foldable sides and end clamped by one of the flanges of the irons, a bottom comprising a plurality of members laced together and loosely supported by the other flange of the irons, and 10 means for detachably connecting said frames.

2. In a foldable boat, upper and lower side and end frames comprising angle sections detachably secured endwise, a bottom comprising a plurality of members having a continuous lacing connection and loosely supported by the lower frame, an end and sides comprising lazy tongs clamped by the said frames independent of the bottom, and 15 a rudder supported by the rear frame and a plurality of detachable sections.

3. In a foldable boat, sectional end and

side frames having flanges, foldable end and sides detachably held by one of said flanges, a foldable bottom loosely supported by the 25 other of said flanges, a waterproof cover attached to the frames and extending under the bottom, and inflatable floats attached to the cover.

4. In a foldable boat, sectional end and 30 side frames, a foldable bottom comprising laced members and loosely supported by certain of the frames, a stanchion connecting the side frames and extending through one member of the bottom for anchoring the latter, a rudder mounted on the end frame, and means for detachably connecting the frame sections for nesting.

In witness whereof I hereunto set my hand in the presence of two witnesses.

ANTON PINTER.

Witnesses:

EMIL SCHURGOT,
ELI McLAUGHLIN.
